2 Claims 10

ABSTRACT OF THE DISCLOSURE

A centrifugally controlled electrical time fuse for a spin stabilized projectile. The projectile has an electrical firing circuit including a timing device having an inductance means in an oscillating circuit thereof. A movable tuning means for said inductance means is responsive to rotational movement of the projectile for varying the frequency of oscillation of the oscillating circuit. The projectile further has means for correlating the energy producing movement of said movable tuning means, which results from the application of centrifugal force thereto occurring as the projectile rotates, with the inductance means. This provides frequency variations of the oscillator circuit indicative of the cumulative number of revolutions of the projectile.

A time fuze is generally employed in a projectile which is to be detonated in its trajectory at a predetermined distance from the gun. The time fuze usually includes a clockwork mechanism which actuates the projectile after the lapse of a predetermined time after the firing of the projectile.

It is presumed that the projectile will have a fixed mean velocity v in its trajectory. Based on this assumption a time t will be set in the clockwork mechanism so that the projectile detonates at a distance $s=v \cdot t$.

However, the mean velocity of the projectile will fluctuate owing to the ammunition and the gun. The effect of this fluctuation of the mean velocity will be compensated by a device which will be able to give the product $v \cdot t$ a constant value for every predetermined distance. For instance, a higher velocity will be compensated by a shorter time in such a manner that $\Delta t/t = -\Delta v/v$.

The present invention relates to an electric device that is provided in a fuze for a projectile that is intended for firing from a gun provided with a rifled barrel, and which device will be able to give the product $v \cdot t$ a constant value for every predetermined distance. The fuze according to the present invention, is provided with a member that is responsive to centrifugal force. This member governs an electric pulse generator in such a way that the pulse frequency of the generator will be directly proportional to the number of revolutions of the projectile. The output of the generator is connected to the input of a pre-adjustable pulse counter. The output of the pulse counter gives a signal when a predetermined number of pulses have been counted. The output of the pulse counter is connected to a means for the electric ignition of the projectile.

With a rotating projectile fired from a gun provided with a rifled barrel, the relation between the number of revolutions and the axial velocity of the rotating projectile is determined by the screw pitch of the terminal rifling at the muzzle of the gun. Consequently, the pulse frequency f is directly proportional to the velocity v that is $f=k \cdot v$ where k is a constant.

The time t for counting n pulses will be $t=n/f$. But as $f=k \cdot v$ it follows that $t=n/(k \cdot v)$ or $n=k \cdot v \cdot t$. But

2

as the distance $s=v \cdot t$ it follows that $n=k \cdot s$. Consequently every pulse interval corresponds to a fixed distance independent of the muzzle velocity of the projectile.

The device which determines the pulse frequency of the generator may comprise a fixed inductance coil provided with an iron or other suitable paramagnetic core that can be displaced or shifted by the centrifugal force of the projectile. The pulse counter may be a standard type well known in this art.

In the drawing,

FIG. 1 is a block diagram of a portion of the electrical circuit in the projectile, and

FIG. 2 is a diagrammatic representation of a longitudinal portion of the projectile with portions broken away to show the internal structure.

The pulse generator is indicated at 1 and it consists of a sine wave oscillator and a pulse shaping device of known character. The output of the pulse generator is connected to the input of the pulse counter indicated at 2. The output of the pulse counter is connected to the input of the means indicated at 3 for the electric ignition of the projectile.

The fuze 4 has a channel 5 perpendicular to the axis 6 of revolution of the projectile. In the channel 5 is an iron core 7 that is movable by centrifugal force during rotation of the projectile and in opposition to the pressure of the spring 8. When the fuze is not rotating, the iron core 7 is maintained inside of an immovable inductance coil 9. This coil 9 is the coil of the oscillating circuit, which circuit is that of the sine wave oscillator 1. When the fuze 4 begins to rotate, the iron core 7 will be moved out of the coil for a certain distance by the action of centrifugal force. If the velocity of the projectile increases, both the number of revolutions of the projectile and the created centrifugal force will increase. When the core 7 is drawn further out of the coil 9, the inductance will decrease. When the core 7 is moved further out of the coil as above stated and the inductance decreases, the pulse frequency of the generator will increase and the results heretofore set forth will accordingly follow.

What is claimed is:

1. A projectile comprising an electrical firing circuit including a timing device having an inductance means in an oscillating circuit thereof;

a movable tuning means for said inductance means, which tuning means is responsive to rotational movement of said projectile for varying the frequency of oscillation of said oscillating circuit;

means for correlating the energy producing movement of said movable tuning means, resulting from the application of centrifugal force thereto and occurring with rotation of said projectile, with said inductance means to provide frequency variations of said oscillator circuit indicative of the cumulative number of revolutions of said projectile;

whereby a counting of said oscillations may be utilized to provide timing out of a desired delay period for the firing of said projectile.

2. A structure as set forth in claim 1, wherein the movable tuning means is a paramagnetic mass and wherein said correlating means is a spring disposed to apply a predetermined biasing force to said tuning means.
